INVENTOR
HENRY J. BEECROFT
By *Arthur L. Slocum*
HIS ATTORNEY.

UNITED STATES PATENT OFFICE

HENRY JOHN BEECROFT, OF SAN FRANCISCO, CALIFORNIA

LIGHTER

Application filed October 30, 1930. Serial No. 492,227.

My invention relates to improvements in electric lighters for cigars and the like wherein a lighting element normally de-energized, is mounted upon one end of a flexible conductor and actuated by the attraction of gravity to move said element into contact with a source of electrical energy when the device is moved to one of several positions, whereby the lighting element may be energized and 10 rendered ready for lighting cigars, cigarettes, and the like.

The primary object of the present invention is to provide a new and improved lighter for cigars and the like.

15 Another object is to provide a new and improved electrical cigar lighter for table use, wherein the lighting element is normally de-energized while the device is placed in a normal or horizontal position upon a table 20 or similar supporting surface when not required for use, and is actuated by the attraction of gravity to move the element into contact with a source of electrical energy, when the position of the device is altered, whereby 25 said element may be energized and rendered ready for lighting purposes.

A further object of the present device is to provide a new and improved lighter which 30 may be rendered ready for use by the simple expedient of changing the position of the device.

35 A further object is to provide a self-contained electrical cigar lighter which shall be compact, convenient and economical in construction and operation, and which may be placed upon a table or similar supporting surface without danger of accidentally igniting adjacent articles.

40 I accomplish these and other objects by means of the preferred form of the device disclosed in the drawing forming a part of the present application wherein like characters of reference are used to designate similar parts throughout the specification and drawing, and in which—

Fig. 1 is a broken plan view of my improved lighter, the element being in a neutral or de-energized position;

50 Fig. 2 is a vertical sectional view taken

on line 2—2 of Fig. 1 in the direction indicated;

Fig. 3 is a front elevation of the device, with the cover removed, showing the same in one lighting position; and

55 Fig. 4 is an enlarged detailed view of the means for permitting and preventing contact with one of the terminals.

Referring to the drawing, the numeral 1 is used to designate a box or housing having 60 a central partition 2 dividing said housing into upper and lower compartments 3 and 4 respectively.

Within the upper compartment 3 I have 65 provided a pair of terminals 6 each slotted vertically from their upper ends as at 7. Within one of the slots 7 I have mounted a flexible conductor 8 extending toward the opposite terminal and having mounted upon its free end and adjacent said other terminal, 70 a suitable lighting element 9 of the type generally used for electrical lighters. A contact 11 is mounted upon the outer side of the element 9 and extends through a preferably square aperture 12 arranged diagonally 75 within a suitable plate 14 so that the sides of said aperture 12 will be inclined with respect to the housing 1, the purpose of which will hereinafter be more fully set forth.

A plurality of dry cells or batteries 16 are 80 stored within the lower compartment 4 and are electrically connected in any suitable manner, not shown, to the terminals 6 so that when the circuit is closed electrical energy within the said batteries will flow through 85 said terminals 6.

Suitable covers are slidably mounted upon the top and bottom of the housing 1 in order to close said compartments, the upper cover 17 being provided with an aperture 18 arranged directly opposite the lighting element 9 within the upper compartment 3.

90 In operation, when the device or lighter is placed in a normal or horizontal position upon a table or other suitable supporting surface, as disclosed in plan view in Fig. 1 of the drawing, the attraction of gravity will move the contact 11 on the heavier end of the conductor 8 having the lighting element 9 attached thereto, into the recess formed by the 95 100

inclined edges of the aperture 12 in the plate 14 which is purposely positioned to prevent engagement of the contact 11 with the adjacent terminal 6 or the internal surfaces of the slot 7 therein, so that the circuit will be broken and the lighting element will at all times, while the housing 1 or lighter is in a horizontal position, be de-energized.

When it is desired to heat the lighting element for any purpose the device is raised and moved to a vertical position as disclosed in Fig. 3 of the drawing. In this position the attraction of gravity will cause the heavier lighting element mounted upon the flexible conductor 8 to move into contact with one of the inner surfaces of the slot 7 of the adjacent terminal 6 and thereby connect the said element 9 with the source of electrical energy through the said terminals 6 and the lighting element will thereby become heated and ready for use.

The cover 17 for the upper compartment 3 is provided with the aperture 18 in order to provide access to the element. If the device should be turned upside down, or face down upon the table, the opposite angle or recess of the aperture 12 of the plate 14 will operate to prevent engagement of the contact 11 with the sides of the terminal 6 and thereby prevent accidental conflagration.

It is obvious that when the device or the housing 1 is in a horizontal position, either upright or up-side-down, that contact or engagement with the adjacent terminal will be prevented by the inclined sides of the aperture 12 of the plate 14, but the device may be placed in numerous positions where the attraction of gravity will operate to move the contact 11 into engagement with the adjacent terminal 6 and thereby connect the lighter element with a source of electrical energy without the manual operation of switches or other devices.

Having thus described my invention what I claim as new and desire to secure by Letters Patent is:—

1. A lighter comprising a housing; a pair of slotted terminals mounted within the housing; a source of electrical energy mounted within the housing and connected to the terminals; a flexible conductor mounted within the slot of one terminal and extending toward the opposite terminal; a lighting element mounted upon the free end of said conductor and adjacent said opposite terminal, said element having a contact extending into the slot of said opposite terminal; and a plate mounted adjacent said lighting element and having an aperture provided with inclined edges surrounding the contact and arranged to prevent engagement of the contact with its terminal when the housing is in one position and to permit engagement of said contact with its terminal when said housing is in another position whereby said

lighting element may be connected to the source of electrical energy and thereby energized.

2. A lighter comprising a housing; a pair of terminals mounted within said housing; a source of electrical energy connected to said terminals; a lighting element flexibly connected to one terminal and extending to a point adjacent the other terminal whereby said element may be moved by gravity to contact said second terminal when said housing is in one position whereby said element may be heated from the electrical energy; and means for preventing contact of said element with said second contact when said housing is in another position.

3. A lighter comprising a housing; a pair of terminals mounted within said housing; a source of electrical energy contained within said housing and connected to said terminals; a lighting element flexibly connected to one terminal and extending to a point adjacent the other terminal whereby said element may be moved by gravity to contact with said second terminal to energize said element, when the housing is in one position; and an insulated plate mounted within said housing for preventing movement of said element to contact with said second terminal when said housing is placed in another position.

In witness whereof, I hereunto set my signature.

HENRY JOHN BEECROFT.
